UNITED STATES PATENT OFFICE.

RAYMOND G. BULLOCK, OF JAMESTOWN, NEW YORK.

LOCK-BOX.

1,172,193.

Specification of Letters Patent.

Patented Feb. 15, 1916.

Application filed February 26, 1913. Serial No. 750,839.

To all whom it may concern:

Be it known that I, RAYMOND G. BULLOCK, citizen of the United States, residing at Jamestown, in the county of Chautauqua 5 and State of New York, have invented certain new and useful Improvements in Lock-Boxes, of which the following is a specification.

The object of this invention is to provide 10 an improved form of lock box for mail. This and other objects of my invention will be fully illustrated in the drawings, described in the specification and pointed out in the claims at the end thereof.

15 In the accompanying drawings, Figure 1 is a perspective view of a series of the lock boxes assembled. Fig. 2 is a horizontal section taken on the line 2^x—2^x in Fig. 1. Fig. 3 is a vertical section on the line 3^x—3^x in 20 Fig. 1. Fig. 4 is a longitudinal vertical section on the line 4^x—4^x in Fig. 2. Fig. 5 is a plan view of the blank from which one of the boxes is formed. Fig. 6 is a perspective view of the blank after it has been formed 25 into a box. Fig. 7 is a perspective view of two of the boxes tied together.

In the accompanying drawings like reference numerals indicate like parts.

In the drawings reference numeral 1 indicates a blank which is cut out of sheet metal 30 and which is bent up to form three sides of a mail box. In this blank are punched blisters 3, 4, 5 and 6. In the blanks are also punched the holes 7^B and 7^A for the tie rods, 35 the use of which will be presently explained. The outline of the blank is made irregular with lugs and recesses for purposes that will also presently be explained.

The middle of the blank, as shown in Fig. 40 5, is perforated with a series of round holes. The edges of these holes are drawn down as is shown in Figs. 3 and 4, and serve to make that part of the blank which is perforated both light and stiff, these perforations being 45 confined to the part of the blank that is intended for the bottom of the box. It also gives to each perforation a round edge instead of a sharp edge, and this prevents to a certain extent the mail matter from catching 50 on the edges of the perforations.

The blank shown in Fig. 5 is bent to the U-shape shown in Fig. 6. On the top of each side of the box is shown a series of lugs 7, 8, 9, 10, 11 and 12. Between these lugs are left

the recesses 13, 14, 15 and 16. As will be 55 seen in Fig. 4, these lugs 7, 8, 9, 10, 11 and 12 are slightly offset from the body of the box so that they will receive between them the bottom of the box that is superimposed thereon, it being understood that these boxes 60 are assembled in vertical series by placing one box upon another. The boxes in a vertical series are tied together in a manner that will now be explained.

Tie rods 17 and 18, 19 and 20, are inserted 65 through the blisters 6, 5, 3 and 4 in vertical series, as is shown in Fig. 7. These rods also fill the openings in the recesses 15, 16, 13 and 14, and by them the boxes in a vertical series are securely held together in a single 70 unit structure.

Referring again to the blank shown in Fig. 5, it will be seen that the blank is provided with a series of sections on the front and rear edge, which are specially cut for 75 purposes that will now be explained.

Sections 21 and 22 are doubled out and back upon themselves to form the reinforced ends 23 and 24. Section 25 is bent down to form the flange 26. Sections 27 and 28 are 80 doubled back upon themselves to form three thicknesses, as is shown in section along the upper edge of Fig. 2. Each of these sections is also provided with a lug, 29 and 30, which extends upwardly therefrom and which is 85 intended to engage with the recess provided in the section at 31 and 32, as shown in the blank illustrated in Fig. 5. See also the dotted line illustration in Fig. 7. The lugs 29 and 30 engage with the recesses left by 90 the cut away portions 31 and 32, making a positive engagement therein, the various parts when bolted up appearing as is illustrated in the section in Fig. 2. The section 33 is bent down and inwardly upon itself to 95 form the reinforced flange 34 shown in Fig. 6.

After the boxes have been formed in the manner above described, they are assembled by placing them in vertical series one on top 100 of the other and fastening them together by the vertical tie rods. Successive vertical series are then placed side by side and these series are tied together by means of the tie rods 35 illustrated in Figs. 2 and 7, these tie 105 rods being threaded on the ends and having the nuts 36 and 37 on the ends thereof by which the parts are held together. These

tie rods need not be used on every horizontal row, it being sufficient to use them on every third horizontal row. The sections so assembled may be mounted upon a suitable base such as is illustrated at 38 in Figs. 3 and 4, which base has cleats 39 and 40 on the front and rear edges thereof, with which the flanges 26 and 34 may engage for the purpose of holding the parts securely in engagement. In the bottom box the flange 34 is preferably left somewhat short so as to engage with the cleat 40. The flanges 34 are also provided with the label holders 41 in which may be placed the name of the tenant of the box.

Beveled mountings 42 and 43 may be provided for the highest and the lowest boxes so as to display the names of the labels to the best advantage to the clerk distributing the mail. Detachable ends 44 and 45 may be placed on each end of the series of boxes for the purpose of closing the ends thereof. On top of the uppermost box is placed a plain panel 46 which completely closes it, and over this a casing 47 for the whole series of boxes may be extended, as is illustrated in Figs. 3 and 4.

To the front of the boxes may be fastened in any suitable manner, such as is illustrated in cross section in Fig. 2, the framework for supporting the hinge doors, by which access to the boxes is controlled from the front. For this purpose the framework is provided with vertical flanges 50, 51 and 52, etc., which flanges extend between consecutive columns of boxes and space them apart, and through which the front edges of the boxes may be riveted or bolted together. The doors 54 are hinged to the flange 53 and the doors 55 and 56 are hinged to the flange 52. The flanges 50 and 51 serve as stops for the doors 54 and 55 and the flange 57 serves as a stop for the door 56.

As shown in Figs. 1 and 2, the doors 54 are hinged on a pin and the doors 55 and 56 are both hinged upon another pin, being placed back to back thereon. Each door is provided with two knuckles and the flanges in each case are provided with stationary knuckles which wholly or partly fill up the space on the pin that is not otherwise taken up by the knuckles on the doors. Where necessary sleeves are placed on the pin in line with the knuckles to fill up the space.

I claim:

1. A letter box formed of a single sheet of metal having a bottom and two upturned sides, said box having its upper edge slightly offset outwardly forming shoulders in the sides to receive the bottom of a box placed above it, the top of each box being closed by the box above it, leaving the front and back of the box open for filling and emptying the box.

2. The combination in a case of letter boxes, of letter boxes arranged in vertical series, each of said boxes being formed of a single sheet of metal and having a bottom and two sides therein, the upper edge of each of the sides being slightly offset to receive the bottom of a box above it, a socket arranged at the side of the box near the bottom, a lug projecting upwardly from the top of each box to engage with a socket at the bottom of the box above.

3. A mail box having a bottom and two sides, the bottom having flanges bent down on each end thereof, each of said sides having its forward edge bent outwardly and back upon itself and having its rear edge bent outwardly and back upon itself, said double portion being again bent outwardly and back upon the box, leaving an interval between itself and the box.

4. A mail box having a bottom and two sides, the bottom having flanges bent down on each end thereof, each of said sides having its forward edge bent outwardly and back upon itself and having its rear edge bent outwardly and back upon itself, said double portion being again bent outwardly and back upon the box, leaving an interval between itself and the box, the upper portion of said folded metal being provided with a lug, a recess in the bottom of said folded portion corresponding to said lug.

5. A metal box having a bottom and two sides, each of said sides having its upper edge offset outwardly to form a socket with shoulders therein to receive the bottom of the box next above it, the top of each box being closed by the box above it, leaving the front and back of the box open for filling and emptying the box.

6. A metal box having a bottom and two sides, each of said sides having its upper edge offset outwardly to form a socket to receive the bottom of the box next above it, recesses in each of said offset portions, blisters formed in the side of the box immediately below said recesses, said recesses and blisters in a series of boxes occurring in line with each other, a locking strip for engaging with the blisters and recesses in a vertical series of boxes.

7. The combination in a case of letter boxes of a series of boxes each formed with a bottom and two sides, said boxes being capable of assembling by stacking them one on top of another, means on each box to positively receive and hold the bottom of the box above it, means for engaging with all the boxes of a series for positively holding them together and in line with each other.

8. In a case of letter boxes, the combination of a series of boxes each formed with a bottom and two sides, said boxes being arranged in a plurality of vertical series,

means integral with said boxes for spacing them apart at the rear, a door frame for covering the front of said boxes, said frame having flanges thereon for engaging between the boxes and holding them apart at the front, said boxes and said flanges being fastened together.

In testimony whereof I affix my signature in presence of two witnesses.

RAYMOND G. BULLOCK.
